(57) **CLAIM**

The ornamental design for a screw type fencing staple, as shown and described.

DESCRIPTION

FIG. 1 is a front, right and top perspective view of a screw type fencing staple, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an environmental front, right and top perspective view of the screw type fencing staple shown in a state of use. The broken line showing of the screw in FIG. 9 illustrates the environment of the claimed design and forms no part thereof.
